UNITED STATES PATENT OFFICE

136,418

DESIGN FOR A SPOON OR SIMILAR ARTICLE

Natalie A. Allo, Escanaba, Mich.

Application July 9, 1943, Serial No. 110,636

Term of patent 7 years

To all whom it may concern:

Be it known that I, Natalie A. Allo, a citizen of the United States, residing in Escanaba, in the county of Delta and State of Michigan, have invented a new, original, and ornamental Design for a Spoon or Similar Article, of which the following is a specification, reference being had to the accompanying drawing, forming a part thereof,

I claim:

The ornamental design for a spoon or similar article, as shown.

NATALIE A. ALLO.
